UNITED STATES PATENT OFFICE.

WILLIAM A. DASHWOOD, OF ST. JOHN, NEW BRUNSWICK, CANADA, ASSIGNOR TO SHEFFIELD CAR COMPANY, OF THREE RIVERS, MICHIGAN.

FLY-WHEEL FOR EXPLOSION-ENGINES.

1,134,110.

Specification of Letters Patent.

Patented Apr. 6, 1915.

Application filed December 18, 1911. Serial No. 666,634.

To all whom it may concern:

Be it known that I, WILLIAM A. DASHWOOD, a subject of the King of Great Britain, residing at St. John, Province of New 5 Brunswick, Dominion of Canada, have invented certain new and useful Improvements in Fly-Wheels for Explosion-Engines, of which the following is a specification.

This invention relates to improvements in 10 fly wheels for explosion engines.

The main objects of this invention are to provide an improved fly wheel for explosion engines which may be conveniently grasped for cranking the engine, no matter 15 what the position of the fly wheel may be.

Further objects, and objects relating to structural details, will definitely appear from the detailed description to follow.

I accomplish the objects of my invention 20 by the devices and means described in the following specification.

The invention is clearly defined and pointed out in the claims.

A structure which is a preferred embodiment of my invention is clearly illustrated 25 in the accompanying drawing, forming a part of this specification, in which:

Figure I is an elevation of a structure embodying the features of my invention, the 30 fly wheel being shown in vertical central section, the engine body and cylinder being shown in conventional form, the base of the engine being omitted. Fig. II is an inside view of the fly wheel, partially in vertical section, on a line corresponding to the broken line 2—2 of Fig. I looking in the direction of the little arrows at the ends of the section lines.

In the drawing, similar reference numerals refer to similar parts in both views.

Referring to the drawing, 1 represents the cylinder and 2 the crank case of an explosion engine. The base is, as stated in the description of Fig. I, omitted. These 45 parts are shown in conventional form.

The crank shaft 3 is provided with my improved fly wheel which, in the structure illustrated, consists of a disk-like web 4 having a hub 5 and a rim 6. The rim 6 has

a portion 7 projecting inwardly from the 50 web, and this inwardly-projecting portion is provided with a continuous series of internal corrugation-like finger holds 8. These finger holds are conveniently positioned for grasping the rim in cranking the engine, 55 and as they are continuous, the rim can be conveniently grasped, no matter what the position of the crank may be.

In cranking some engines, it is customary for the operator to grasp the spokes, or to 60 grasp the rim adjacent to the spokes. This is quite a dangerous practice, and many accidents have occurred by reason of the operator being struck by a spoke when the wheel is jerked from his hands, or being unable 65 to release his hold quickly enough owing to the position in which he has to place his hands in order to grasp the wheel. My improved fly-wheel can be conveniently grasped in any position, and there is practically no danger in cranking the engine. It can be securely grasped, and, at the same 70 time, it is easily released, or if jerked from the operator's hands, they are positioned so that no serious injury can result.

Having thus described my invention, what I claim as new and desire to secure by Letters Patent is:

1. In an explosion engine, the combination with the crank shaft, of a fly wheel 80 therefor comprising a web and rim, the rim having a portion projecting inwardly from said web, the inner side of said inwardly-projecting portion being fluted or corrugated to provide a plurality of finger-holds. 85

2. In an explosion engine, the combination with the crank shaft, of a fly wheel comprising a substantially solid web and a rim provided with internal corrugation-like finger holds adjacent to its inner edge. 90

In witness whereof, I have hereunto set my hand and seal in the presence of two witnesses.

WILLIAM A. DASHWOOD. [L. S.]

Witnesses:

GRACE COSTER,
G. EARLE LOGAN.
